Application July 17, 1950, Serial No. 174,216

5 Claims. (Cl. 62—7)

1

This invention relates to refrigeration, and more in particular to making ice in the form of cubes or the like by the use of machines such as those disclosed in the copending applications of Meldon, Gerald Leeson, Serial No. 573,939, filed January 22, 1945, and Serial No. 686,021, filed July 24, 1946, now Patents 2,524,815 and 2,549,747, and of William M. Grandia, Serial No. 57,158, filed October 29, 1948; now Patent No. 2,593,874.

The above-identified applications disclose machines and methods for making ice in the form of cubes which may have cylindrical holes therethrough. The illustrative embodiment of the present invention comprises an ice-making machine or apparatus which, except as specifically pointed out, is identical with that disclosed in application Serial No. 57,158, now Patent No. 2,593,874 which, in turn, incorporates specific structure shown in application Serial No. 686,021, now Patent No. 2,549,747. The structure herein disclosed is therefore described only sufficiently for the understanding of the present invention, and reference may be had to the above-identified copending applications for more detailed discussions of certain features of construction and operation of this general type of apparatus.

It is an object of the present invention to provide improved apparatus of the above character and to provide an improved mode of operation thereof. It is a further object to provide improved modes of operation and control for apparatus of the above character. It is a further object to provide for the above with apparatus which is practical in every respect from a commercial standpoint. These and other objects will be in part obvious and will in part be pointed out below.

The invention accordingly consists in the features of construction, combinations of elements, and arrangements of parts as will be exemplified in the structure to be hereinafter described and the scope of the application of which will be indicated in the following claims.

In the illustrative embodiment of the invention disclosed in application Serial No. 57,158, now Patent No. 2,593,874, ice cubes are formed by first freezing the water to form ice rods or columns which are square in cross-section and may have a cylindrical hole therethrough, and these columns are melted free and then are cut or broken into lengths to form the cubes. The columns of ice are formed by flowing water through vertical freezing tubes which form passageways along the side walls of which the water

2

flows while these walls are refrigerated sufficiently to cause ice to build up. The rate of flow and the other conditions are so controlled that clear, hard ice builds up in an even layer and the freezing operation is continued until the column is substantially solid or, if desirable, has a hole of predetermined size therethrough.

A harvesting operation is then started which involves melting the tubes free so that they fall from the tubes, and as they emerge from the bottoms of the tubes they are severed into predetermined lengths to form the cubes. During the freezing operation water is circulated through the tubes at a rate which is in excess of the amount frozen, and the water in excess of that which is frozen is collected in a sump tank to which fresh water is added and from which water is pumped and recirculated through the freezing tubes.

With apparatus such as that referred to above, difficulty has been encountered in producing uniform high quality ice without frequent adjustment and cleaning. Machines such as those referred to above have, however, been sold as "package units"; that is, self-contained units are built and sold for installation by the purchaser, and are put into operation by making connections to the water supply and drain and to a source of electric power. The operation is then automatic with the ice-making and harvesting operations being carried on in accordance with a controlled cycle. Under some circumstances the salt concentration is high so that there is a tendency for the ice to become cloudy and commercially unacceptable, and special care must be taken to maintain the salt concentrations within permissible limits. It is advisable, however, to avoid complicated and costly equipment and to use a minimum amount of water consistent with the production of maximum quantities of commercially acceptable ice.

An important feature of this type of equipment from a commercial standpoint is that the ice produced is uniform in size and shape and, of course, is of high quality; that is, the ice cubes are clear and hard and of substantially the same size and shape. It has been found, however, that apparatus such as that referred to above will, under some conditions of operation, produce ice which is not uniform and, in fact, which is not entirely satisfactory from a commercial standpoint. For example, if the ice builds up at an excessive rate in one particular tube it may freeze solid and become sub-cooled excessively prior to the end of the freezing cycle and then

part or all of it may not become dislodged during the harvesting cycle. If due to this or another cause, a body of ice remains in one of the freezing tubes after a harvesting cycle has been completed, there is great danger that the tube will be damaged during the next freezing operation.

Provision has been made in apparatus of the above character for preventing the completion of a freezing operation if one or more of the tubes are obstructed. However, it is still important to insure that ice builds up at the desired rate in all of the freezing tubes. As indicated above, with this type of apparatus, when water is flowed down the inner walls of the freezing tubes at a very rapid rate, clear and hard ice forms in an even layer. This is because the rapidly flowing layer of water covers the entire inner surfaces of each of the tubes, and this effect has been obtained by projecting individual streams of the water against the top of each of the four side wall surfaces of each tube. Thus four streams are projected into each tube from corresponding outlets or openings in a nipple or water distributor in the bottom of a water header where the water is maintained under pressure by the water circulating pump referred to above.

In practice, however, it has been found that one or more of the outlets from these nipples may become clogged; for example, by the accumulation of foreign matter including coagulated or crystallized salts when the salt concentration is high. When one or more of the water outlets in a nozzle becomes clogged there is a corresponding decrease in the rate at which water flows through that tube. Thus, while the water may tend to spread out over the entire inner surface of that tube, the rate of water flow is reduced because of the lesser quantity which is being delivered to the tube. This reduced rate of water flow not only causes the ice in that tube to become cloudy and have white streaks running through it, but this reduced rate of flow causes the ice to build up at an increased rate so that that particular tube becomes filled with a column of ice prior to the completion of the freezing operation in the other tubes. For example, ice may completely fill one tube while relatively thin shells are being formed in the other tubes.

In the apparatus of Serial No. 57,158, now Patent No. 2,593,874, the harvesting operation is initiated whenever one or more of the tubes become filled with ice sufficiently to interfere materially with the flow of water therethrough. This has been extremely satisfactory as a mode of control for most conditions of operation because the freezing is uniform in the various tubes and they all become substantially filled with columns of ice of high quality at substantially the same time; that is, by the time one or more of the tubes have the water flow obstructed by the ice sufficiently to initiate the harvesting operation. However, with such control it has been found that, when there is an obstruction as discussed above in one or more openings in a nipple supplying water to a tube, so that ice builds up and fills that tube with ice prematurely in the cycle, then a harvesting cycle is also started prematurely. As indicated above, under such circumstances the one tube having obstructions in its water supply openings is filled with poor quality ice while the other tubes have only shells of ice in them and, therefore, the apparatus produces no ice of acceptable quality and size.

In accordance with the present invention, an

arrangement is provided for insuring that the water will be distributed evenly and will flow continuously down all of the tube surfaces throughout the entire freezing cycle. The invention contemplates a water distribution arrangement wherein solid particles such as crystallized salts or foreign matter will not interfere with this flow. Thus, the freezing cycle will be carried on to completion without danger of being stopped by the premature building up of ice in the tube. Furthermore, the water is delivered to the tubes in such a manner that it does not tend to flow at a reduced rate through any area of the freezing surfaces of the tubes.

In the drawings, in which is shown one embodiment of the invention:

Figure 1 is a schematic diagram of an ice-making machine of the character referred to above and incorporating the present invention;

Figure 2 is a top plan view with parts broken away of the water distributor header of Figure 1;

Figure 3 is a side elevation with parts broken away of the header of Figure 2;

Figures 4, 5 and 6 are sectional views respectively on the lines 4-4, 5-5 and 6-6 of Figure 3;

Figure 7 is a section on the line 7-7 of Figure 6; and

Figure 8 is a view similar to Figure 7 but showing another embodiment of the invention.

Referring to Figure 1 of the drawing there is represented schematically at the top a bank of freezing tubes 1 to the tops of which water is directed by a header 3 supplied by a pump 5 from a sump tank 7. The water flows down the tubes and some is frozen, and the amount in excess of that frozen in the tubes returns to the sump tank. A float valve 8 connected to a source of water opens and closes automatically to maintain a pre-determined level in the tank. The freezing tubes are cooled by an evaporator 9 to which liquid refrigerant is supplied through a thermostatic valve 11 having a bulb 13. The gas refrigerant from the evaporator is withdrawn by a compressor 15 having an electric motor 14 hermetically sealed within its casing. The compressed gas passes from the compressor 15 to a water-cooled condenser 17 cooled by water supplied through a valve 18. The refrigerant is here liquefied and passes to the evaporator. During the harvesting cycle hot gas refrigerant is passed from the compressor to the evaporator to heat the freezing tubes; accordingly, a pipe 19 (indicated by broken lines) is provided having a normally-closed solenoid valve 21 therein which valve is opened to connect the outlet side of the compressor to the bottom of the evaporator.

Power to operate the machine is supplied through a main control switch 23 to a pair of lines 25 and 27 which are connected directly to the compressor motor. Line 25 is also connected to the armature 29 of a double-throw solenoid switch 31 and also to one side of a thermostatic switch 33. Line 27 is connected to one side of each of the solenoid valves 24, the ice cutter motor 37 which operates the mechanism to cut the ice into cubes, the water pump motor 39 which drives pump 5, and the solenoid 41 of switch 31. Switch 31 has a contact 43 which is closed when the switch has its solenoid de-energized, and this contact is connected to the other side of the solenoid of valve 21 and also to the other side of motor 37; and it has its normally-opened contact 45 connected to the pump motor 39 and also to one side of a thermostatic switch 47. The other side of switch

47 is connected to solenoid 41 and to switch 33. The operation of the machine will be explained after the construction of the water distributor and the associated parts have been explained in detail.

Referring to the upper portion of Figure 1, there is shown the bank of square freezing tubes 1 positioned in side-by-side relationship with a plate 48 between the side walls of each two adjacent tubes. On the opposite sides of the bank of tubes there are two evaporator sections of evaporator 9 formed by horizontal runs of metal tubing with the sections being connected by headers. The bank of freezing tubes and the evaporator sections are covered by insulation and enclosed in a sheet metal casing. At the top of the bank of tubes there is a horizontal water supply header 3 which is enclosed in an insulation shell, and projecting from the bottom wall of this header into the top of each of tubes 1 is a water distributor nozzle 54 which directs water against the inner surfaces of the four walls of its tube.

At the bottom of the freezing tubes there is an ice-cutting assembly which is not shown but is shown and described in detail in the above-identified applications. This assembly severs the columns of ice which are formed in the tubes into lengths to form the ice cubes which are passed by gravity to a storage bin. At the beginning of the harvesting operation the columns of ice are released by passing hot gas into evaporator 9 and at the same time the ice cutter assembly is started. This operation continues until the temperature of the evaporator rises, thus indicating that the ice has been freed and has dropped from the freezing tubes. At this time the harvesting operation is discontinued and a new freezing operation is started. As indicated above, during the freezing operation water is pumped into header 3 at the top of the freezing tubes and it flows down the entire inner surfaces of each of these tubes. The construction of header 3 is shown in Figures 2 to 7 and will now be described.

Referring to Figure 2, a unitary elongated metal shell 60 is fabricated of separate plates and has side walls 62 and 64, a right-hand end wall 66, a removable left-hand end wall 68, a top wall 70 (see Figure 3), a bottom wall 72 and a horizontal longitudinal dividing wall or partition 74. End wall 68 is clamped in place by a pair of bolts 76 which are held by a pair of angle brackets 78 welded to the side walls, and a gasket 80 on the inner surface of the end wall provides a seal. The header is clamped in place on the bank of tubes by bolts (not shown) extending through a plurality of tubular brackets 82 welded to the side walls of the shell, and the entire shell is covered with heat insulation 84. Partition 74 divides the space within the shell into a lower water-supply header or passageway 86 below the partition and an upper water outlet passageway 88.

Referring to Figure 1, water is supplied to passageway 86 through a pipe 90 which extends from pump 5; and the water discharge passageway 88 has a water outlet pipe 91 extending downwardly and projecting into the enlarged upper end of a pipe 95 which extends to the sump tank 1. A thermostatic bulb 97 of switch 47 is positioned in pipe 95 with its tube 98 extending upwardly and out of the top of the pipe. This bulb is so positioned that water from pipe 91 flows over the bulb as it flows downwardly along

70 75

pipe 95 to the sump tank. The cooling of bulb 97 opens switch 47 and initiates the harvesting cycle as discussed above.

Referring to Figures 2, 3 and 4, header 3 has mounted in its bottom wall the water distribution nozzles 54 which correspond in number to the freezing tubes and are positioned respectively at the tops of the tubes in axial alignment therewith. Each of these nozzles comprises means forming a water distributor through which water is supplied from passageway 86 to the top of its tube, and also overflow discharge means connecting the top of the tube with the water discharge passageway 88. Each nozzle 54 is formed by a bolt-like pipe 114 and an end target or deflector 106, which acts as a spreader, and which is threaded onto the lower end of the pipe, and the upper end of the pipe is rigidly supported by a threaded engagement in an opening 118 in partition 74. Pipe 114 projects through a water discharge opening 104 in bottom wall 72 and deflector 106 is positioned beneath this wall in the top of the freezing tube 1. The deflector presents a top spreader or target surface 108 which is annular and is positioned concentrically with the annular discharge opening 104. Thus, as water flows downwardly from the discharge opening it is projected against this surface 108 and is deflected annularly against the top of the inner surfaces of the freezing tube. Thus, unobstructed passageways are provided from header passageway 86 into the tops of the freezing tubes and the downwardly flowing stream of water is intercepted by the target or deflector to divert the water in an annular stream against the tube walls. In the embodiment of Figure 8, the deflector 106 has a plurality of radial vanes 128 which assist in diverting the water against the tube walls.

The upper end of pipe 114 projects substantially above partition 74 and therefore the pipe provides an overflow discharge from the top of its freezing tube into passageway 88 so that water may flow from the freezing tube upwardly through the pipe and overflow in the passageway. As indicated above, passageway 88 is provided with a water outlet pipe 91 through which water flows freely with the result that the water level in passageway 88 does not rise above the upper ends of pipes 114; therefore, water does not flow up one of these pipes and thence back down another into the freezing tubes. As shown at the right-hand end of Figures 2 and 3, passageway 88 has a vent tube 120 which vents this passageway to atmosphere, and it also provides an emergency outlet for water if there should be a stoppage of pipe 91.

During operation, as outlined above, water flows up through pipe 90 into passageway 86 and it is discharged through the nozzles 54 into the tops of the freezing tubes. The path of the water is unobstructed so that particles of crystallized salts and even foreign matter of substantial size can pass through passageway 86 and then through the nozzles and down the freezing tubes into the sump tank. Such a foreign particle might be of sufficient size to momentarily interfere with the water flow through a nozzle but the particle will not become lodged because the rapid water flow carries it along.

As indicated above, during the freezing operation water is pumped into header 3 at the top of the freezing tubes and it flows down the entire inner surfaces of each of the freezing tubes. The refrigeration system is operated to maintain the freezing tubes at a temperature low enough

to produce a relatively rapid formation of ice on the inner surfaces of the freezing tubes. This ice builds up within the tubes in the form of columns having cylindrical openings therethrough. As the freezing continues these openings become smaller until the free flow of water through the freezing zone, that is, beneath the nozzles, is interfered with; and, at that time, the freezing operation is stopped and the harvesting operation is started.

The backing up or accumulating of water at the entry to the freezing zone is utilized to perform the function of stopping the freezing operation and starting the harvesting operation. Accordingly, when the water backs up in one of the freezing tubes, the pressure from header 86 causes the water to flow up pipe 114 and into passageway 88 as discussed above. This water flows from passageway 88 through pipe 91 (see Figure 1) downwardly over thermostatic bulb 97, and the water is cold so that it cools this bulb. This initiates the harvesting operation by opening switch 47 as will be discussed more fully below.

Positioned near the top of the central freezing tube is the bulb 99 (Figure 1) of thermostatic switch 33. Thermostatic switch 33 is so adjusted that it closes when the temperature of the freezing tubes is substantially above 32° and the switch opens again when the temperature drops below 32°, and thermostatic switch 47 is closed when the temperature of its bulb 97 is above 44° and this switch opens when the temperature of its bulb drops below a 38° temperature. In Figure 1 the elements are shown at the start of the freezing cycle when the freezing tubes are still at ambient temperature. Thus, the closing of switch 33 starts the compressor motor 14 and switch 33 being closed solenoid 41 is energized so that its armature 29 is lifted. The raising of this armature opens the circuit of the ice cutter motor 37 and solenoid 21 and it energizes the water circulating pump motor 39 so that water is supplied to the freezing tubes. Furthermore, the raising of armature 29 energizes switch 47 and this switch being closed an interlock circuit is set up for switch 31 thus connecting solenoid 41 through armature 29, contact 45, and switch 47 to line 25. Therefore, when the temperature of the freezing tubes drops so that switch 33 opens this interlock circuit holds solenoid 41 energized and continues the freezing operation as long as switch 47 is closed.

During normal operations switch 47 remains closed until at least one of the columns of ice has its central opening reduced sufficiently to materially restrict the flow of water therethrough. At that time the water backs up as outlined above in the top of the freezing tube and flows through the pipe 114, passageway 88 and pipe 91, and falls onto bulb 97. This immediately cools the bulb and opens switch 47 so that solenoid 41 is deenergized and armature 29 drops. This disconnects line 25 from pump motor 39 so that water is no longer supplied to the freezing tubes. Armature 29 falls into engagement with contact 43 so that line 25 is connected to solenoid valve 21 and the ice cutter motor 37, the other side of each of which is connected to line 27. Therefore, solenoid valve 21 is opened and the cutter motor is started, thus initiating the harvesting operation. The operation of the compressor continues so that the opening of valve 21 causes the hot refrigerant gas to flow from the compressor to the evaporator. This

heats the freezing tubes so that the columns of ice are released and the ice cutter motor 37 is operated to cut the ice into cubes as outlined above. The harvesting operation continues until the temperature of the freezing tubes rises to a value which indicates that they are free of ice at which time a new freezing cycle is started and the cycle of operations is then repeated.

With this arrangement the ice freezes through substantially the same thickness at all times even though there are variations in the ambient and water temperatures. Furthermore, if for any reason there is a stoppage in one of the tubes due to a failure of the ice to clear during the previous harvesting operation the freezing operation will be terminated and a harvesting operation will be started immediately. It has been found that the water flow is uniform and constant even under extreme conditions, such as the presence of foreign matter or very high salt concentrations and the like. Thus, the difficulties referred to above as well as others are avoided and uniform ice of extremely high quality is produced. Furthermore, the apparatus does not need servicing it being merely necessary to flush out the sump tank periodically to remove solid particles therefrom.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

We claim:

1. In apparatus of the character described, the combination of, ice forming means including, a plurality of refrigerated passageways through which liquid to be frozen flows and within which ice forms so as to restrict the flow near the end of a freezing operation, means to supply the liquid to be frozen to said passageways comprising a plurality of individual nozzles each of which has a single outlet and which are substantially unrestricted in the sense that they will pass water containing particles of foreign matter and salts, means forming a discharge outlet from each of said passageways adjacent the liquid inlet, and control means responsive to the flow of liquid through said outlet to discontinue the freezing operation.

2. In apparatus of the character described, the combination of, means forming a plurality of refrigerated passageways through which liquid to be frozen flows and within which ice forms, and liquid distributing means including, a liquid inlet passageway and a plurality of liquid discharge nozzles and overflow outlets each of which is formed by structure forming a single center passageway and a surrounding annular passageway through which liquid flows, and target means in the path of the incoming stream.

3. In apparatus of the character described, the combination of, ice forming means including a plurality of parallel freezing tubes which are positioned in side-by-side vertical relationship, and a header assembly comprising means forming inlet and outlet compartments and a plurality of nozzle assemblies each connected therewith and each of which includes, a central pipe and a concentrically positioned collar surrounding said pipe thereby providing an annular passageway concentric with the passageway through the pipe, said nozzle assemblies corresponding in number with the tubes and being respectively

associated therewith to deliver water thereto and to permit water to overflow therefrom, whereby water may flow through one of said passageways to said tube and through the other of said passageways from said tube, each of said nozzle assemblies including an unobstructing water-diverting means to divert the water entering the tube against the tube walls.

4. Apparatus as described in claim 3 wherein each of said nozzles includes, a substantially disc-like member which constitutes the water-diverting means and which has an annular diverting face positioned in alignment with said annular passageway, said disc-like member including a plurality of radial vanes extending along said annular surface.

5. In ice making apparatus in which ice is formed in a plurality of refrigerated vertical tubes by flowing liquid through said tubes, a liquid header assembly above said tubes comprising, a supply header, means forming water supply orifices leading from the supply header

5 to the tops of said tubes, spreader plates associated with said orifices to spread the liquid flowing from the supply header through the orifices thereby to direct the liquid against the tube walls, and means forming a discharge header connected to the top of each of said tubes and so arranged that liquid overflows from the tops of the tubes into said header.
